UNITED STATES PATENT OFFICE.

EDWARD J. BARCALO, OF BUFFALO, NEW YORK, ASSIGNOR TO BARCALO MANUFACTURING COMPANY, OF BUFFALO, NEW YORK.

DESIGN FOR A SIDE PANEL FOR CHILD'S CRIB OR SIMILAR ARTICLE.

Application filed June 12, 1925. Serial No. 13,759. Term of patent 3½ years.

To all whom it may concern:

Be it known that I, EDWARD J. BARCALO, a citizen of the United States, residing at Buffalo, in the county of Erie and State of New York, have invented a new, original, and ornamental Design for a Side Panel for a Child's Crib or Similar Article, of which the following is a specification, reference being had to the accompanying drawing, forming a part thereof.

The accompanying drawing is a face view of a side panel for child's crib or similar article embodying the design.

I claim:

The ornamental design for a side panel for a child's crib or similar article, substantially as shown.

EDWARD J. BARCALO.
